RUFFLING MECHANISM FOR SEWING MACHINES

Arthur L. Plamondon, West Newton, and Roland A. Matthies and Owen K. Iversen, Needham, Mass.

Application November 25, 1939, Serial No. 306,066

6 Claims. (Cl. 112—132)

This invention relates to ruffle mechanisms for sewing machines and its objects, broadly stated, is the provision of such mechanism of improved and simplified construction that is adapted for use especially on commercial sewing machines of the high speed type, although it is capable of more general application.

For an understanding of the invention and an illustration of one of the many embodiments thereof, reference may be had to the accompanying drawings, in which:

Figure 1 is a side elevation of an overseaming sewing machine of the Merrow type to which our invention has been applied.

Fig. 2 is an end elevation of the machine shown in Fig. 1, the ruffler blade being shown in inoperative position.

Fig. 3 is a transverse vertical section taken on the line 3—3 of Fig. 1.

Fig. 4 is a transverse vertical section taken on the line 4—4 of Fig. 1.

Fig. 5 is a longitudinal horizontal section taken on the line 5—5 of Fig. 1.

Fig. 6 is a fragmentary end view corresponding to Fig. 2, but showing the ruffler blade in operative position at the beginning of its forward movement along the work plate.

Fig. 7 is a corresponding view showing the ruffler blade at or near the end of its forward stroke.

Fig. 8 is a section taken on the line 8—8 of Fig. 2, and

Fig. 9 is a fragmentary plan view of the ruffler blade and its associated parts.

In the particular drawings selected for more fully disclosing the principle of the invention, 19 represents the base of a sewing machine, and 11 the base that carries the ruffling mechanism, the two bases being secured together by any suitable means, such as screws, one of which is shown at 12.

The ruffling mechanism base is provided with a forwardly extending platform 13, cast with two upstanding ears 14, 15, which afford bearings for the driving rock-shaft 16 and the driven rock-shaft 17, respectively. At one end of said driven shaft is connected, in any suitable manner, an arm 18 carrying at its upper end a plate 19 to which is attached the ruffler blade 20, while at the opposite end of the machine the slotted arm 21 is rigidly secured to the outer end of the driving rock shaft, as by the screws 22, 22, or other suitable means. In any convenient way, such as by means of the eccentric 23, mounted on the main shaft 24 of the sewing machine, the con-

necting arm 25, the cross head 26, and the pin 27 held by the nuts 28, 28, in adjusted position in the slot 29, rocking motion through any desired arc may be imparted to the arm 21 and communicated to the driving rock-shaft 16.

It will be obvious that if the two rock-shafts are coupled, the blade-carrying arm 18 will be rocked through the same arc as the slotted arm 21.

Ruffling mechanisms actuated by two rock-shafts that may be coupled automatically or manually for intermittent action without stopping the machine are not new, but the problem confronting us was the provision of a simplified coupling mechanism whereby a ruffle applied to a high speed machine could be operated at will by manually controlled coupling means.

Our solution of this problem comprises two coaxial rock-shafts, one driving and the other driven, and each restrained from axial movement with respect to the other, together with a sleeve enclosing the proximate ends of said rock-shafts, said sleeve being rigidly secured to the driven rock-shaft, and any suitable manually actuated means for connecting said sleeve at will for oscillation by the driving rock shaft.

In the particular embodiment of the invention shown in the accompanying drawings, said manually actuated means co-operates with a plunger carried by and mounted for relative movement with respect to the sleeve whereby said plunger normally held out of engagement with the driving rock-shaft, may be brought into cooperative engagement therewith. A simple means for attaining this result is shown in the particular embodiment of the invention illustrated in the accompanying drawings, viz., the plunger is provided with a conical inner end which by said manually actuated means may be forced into a conical depression in the driving rock-shaft, thereby locking said rock-shaft to the sleeve which, as aforesaid, is rigidly secured to the driven rock-shaft.

In the present instance, the means for restraining the driving rock-shaft from axial movement to the right (from the aspect of Fig. 1, showing the side of the machine which faces the operator) is the collar 30, rigidly secured to said rock-shaft by the set screw 31 and abutting the ear 14. Axial movement of the driven rock-shaft 17 to the left is restrained by the sleeve 32, which is rigidly connected to said rock-shaft by the screws 33 and the left-hand end of which abuts the ear 15. Axial movement of the driven rock-shaft to the right, and of the driving rock-shaft 55

to the left, is prevented by the abutting of the inner ends of said rock-shafts, as indicated at 34. Both rock-shafts being restrained from axial movement and said sleeve being rigidly secured to 5 one of them, it follows that there is no relative movement between said sleeve and either rock-shaft. As shown, the sleeve 32, which encloses the proximate ends of the rock-shafts, is provided with a tubular boss 35 intermediate its ends 10 which serves as a guide for the plunger 36 mounted therein for relative movement with respect to said sleeve and normally maintained out of engagement with the driving rock-shaft by the compression spring 37 interposed between the head 38 of said plunger and the upper end of said boss. Preferably, the inner end of the plunger is cone-shaped, as indicated at 39, and is disposed to enter the similarly shaped peripheral depression 40 formed in the driving rock-shaft (Fig. 4). 15 Obviously, when the inner end of the plunger takes into said depression the driving rock-shaft will be locked firmly to the sleeve 32 which, as aforesaid, is rigidly secured to the driven rock-shaft, whereby the oscillatory movement of the 20 slotted arm 21 will be communicated to the ruffler blade arm 18. 25

The means for actuating the plunger 36 at will is shown in the illustrated embodiment of the invention as the lever 41 pivotally connected at 30 its inner end by the pin 42 to the post 43 up-standing from the ruffling mechanism base 11. The outer end of the lever, which of course may be actuated by hand, is provided with a hole 44 for receiving a wire or rod attaching means, the lower end of which may be connected to the usual treadle (not shown) employed for controlling the movements of parts of sewing machines. Preferably, an adjustable stop 45 may be attached to the slotted guide 46 for said lever by the screw 40 47 for limiting the downward movement of said lever. It will be understood, of course, that the aperture in the driving rock-shaft and the lower end of the plunger need not be shaped as shown in the drawings and that my invention is not to 45 be limited thereto, but comprises within its scope various other means whereby the plunger may, at will, be brought into co-operative engagement with the driving rock-shaft.

If it be desired to actuate the ruffler blade 50 continuously, the driving shaft may be rigidly secured to the sleeve in any suitable manner, as by the set screws 48 (Fig. 5).

We have found that by the coupling means above described, the ruffling mechanism may be 55 stopped and started at will even when attached to a high speed commercial machine, for example, one running at 4,000 revolutions per minute, in which case, the rock-shaft will make 8,000 oscillations a minute, while with the machines 60 of the prior art in which the clutches or rock-shaft couplers are relatively movable with respect to the shafts, such result is quite impossible of attainment.

Unless the surface of contact of the lower face 65 of the lever 41 with the head 38 of the plunger is carefully designed mechanical vibration at the rate of 8,000 oscillations per minute will be imparted to said lever, and such movement communicated to the treadle will produce an unpleasant 70 sensation in the foot of the operator. We have found that no appreciable movement is imparted to the lever if the surface of contact thereof with the plunger is made arcuate, as shown at 49, and given a radius of curvature 75 equal to the distance between the center of the

driving rock-shaft and the outer end of the plunger when the inner end thereof is seated in the depression 40, or, generically expressed, a radius of curvature equal to the distance between the center of the driving rock-shaft and the outer end of the plunger when the latter has been put into operative engagement with said driving rock-shaft.

Preferably, means are provided for automatically moving the ruffler blade into operative position in contact with the stripper 50, attached by the screws 51 to the work plate 52 which, in the present instance, is pivoted to the stud 53, upon the commencement of the ruffling operation, and other means are provided for automatically raising the ruffler blade from the work plate upon cessation of such operation. In the illustrated embodiment of the invention, the ruffler arm 18 is rigidly clamped to the driven rock-shaft 17 by the split hub 54 and screws 55, and at the upper end thereof the ruffler blade supporting plate 19 is pivoted by the screw 56 which passes through the hub 57 formed integral with said plate, and through the upper end of the arm 18, a nut 58 being threaded to the end of said screw that projects through said arm. Rigidly attached to the ruffler blade plate is a finger comprising a forward portion 59 overlying said plate and secured to the rearward end thereof by the screws 60 and extending rearwardly of the pivotal connection of the ruffler blade with the arm 18, such rearward extension consisting of a diagonal part 59' which terminates in a portion 59'' extending downwardly and vertically into the plane of the finger stop means herein shown as the screw 60 threaded into the up-standing plate 61 attached to the ear 15. By means of the nut 62 the screw 60 may be held in adjusted position with respect to the depending finger 59'.

Attached to the side of the arm 18 by the screw 63 is an angle piece 64 to which is connected the lower end of a spring 65, the upper end of which is secured to the under side of the blade plate and exerts thereon a downward pull at a point between the working end of the ruffler blade and its pivotal connection to the arm 18, whereby the said blade is held against the work plate, or the stripper attached thereto, when the depending finger is out of engagement with the finger stop 60. In Fig. 2, showing the normal position of the arm 18 when the ruffler is not in operation, it will be noted that the lower end of said depending finger is in engagement with the finger stop and that thereby the ruffler blade is automatically raised from the work plate so as not to interfere with the sewing operation. The arm 18 is brought to its retracted position by means of the spring 66, the respective ends of which are attached to the angle piece 64 and the up-standing plate 61, and through said plate is threaded the arm stop 67 held in adjusted position by the nut 68. The two stop screws are so adjusted that upon the release of the lever 41, which permits the spring 66 to retract the arm 18 to normal position, the depending finger comes into contact with the screw 60 immediately prior to the contact of said arm with the arm stop means 67, whereby the ruffler blade is moved clockwise around its pivot until said arm reaches the end of its retrograde movement. In this position, the parts remain until rocking movement again is imparted to the driven rock-shaft, whereupon, as shown in Fig. 6, immediately after the depending finger has been moved away from 70 the stop screw 60, the spring 65 pulls the ruffer blade down upon the stripper along which it moves toward the presser foot 69, Fig. 7 showing the position of the parts at or near the end of the forward stroke of the ruffer blade. At all times during the operation of the ruffling mechanism, the spring 66 is under tension and immediately upon release of the lever 41, such tension exerted on the arm 18 through the angle piece 64 10 draws said arm back against the stop 67, thereby automatically restoring the ruffer blade to inoperative position out of contact with the work plate, as illustrated in Fig. 2.

Having thus disclosed an illustrative embodiment of our invention without, however, limiting ourselves thereto, what we claim and desire to secure by Letters Patent is:

1. The combination with a sewing machine having a main shaft, of ruffling mechanism comprising a driving rock-shaft connected for operation by said main shaft, said driving rock-shaft having a peripheral depression, a driven rock-shaft coaxial with said driving rock-shaft, a ruffer blade, means connecting said ruffer blade 20 for actuation by said driven rock-shaft, a sleeve enclosing the proximate ends of said rock shafts, means rigidly securing said sleeve to said driven rock-shaft, a plunger carried by and mounted for relative movement with respect to said sleeve, 25 means normally maintaining the inner end of said plunger out of the depression in said driving rock-shaft and manually actuated means for moving the inner end of said plunger into said depression in said driving rock-shaft.
- 35 2. The combination with a sewing machine having a main shaft, of ruffling mechanism comprising a driving rock-shaft connected for operation by said main shaft, a driven rock-shaft coaxial with said driving rock-shaft, a ruffer blade, 40 means connecting said ruffer blade for actuation by said driven rock-shaft, a sleeve enclosing the proximate ends of said rock-shafts, means rigidly securing said sleeve to said driven rock-shaft, a plunger carried by and mounted for relative movement with respect to said sleeve, 45 means normally maintaining said plunger out of engagement with said driving rock-shaft and manually actuated means for bringing said plunger into co-operative engagement therewith.
- 50 3. Ruffling mechanism for sewing machines comprising in combination, a driving rock-shaft restrained from axial movement, a driven rock-shaft coaxial therewith and restrained from axial movement with respect thereto, a ruffer blade, 55 means connecting said ruffer blade for actuation by said driven rock-shaft, a sleeve enclosing the proximate ends of said rock-shafts, means rigidly securing said sleeve to said driven rock-shaft, and manually actuated means for connecting said sleeve at will for oscillation by said driving rock-shaft.
4. Ruffling mechanism for sewing machines comprising in combination, a driving rock-shaft having a peripheral depression, a driven rock-shaft, 60 a ruffer blade, means connecting said ruffer blade for actuation by said driven rock-shaft,

a sleeve enclosing the proximate ends of said rock-shafts, means rigidly securing said sleeve to said driven rock-shaft, a plunger carried by and mounted for relative movement with respect to said sleeve, means normally maintaining the inner end of said plunger out of the depression in said driving rock-shaft and a manually actuated lever pivoted at one end and disposed for co-operation with the outer end of said plunger to move the inner end thereof into said depression, the surface of contact of said lever with said plunger being arcuate and having a radius of curvature equal to the distance between the center of said driving rock-shaft and the outer end of said plunger when the inner end thereof is seated in said depression in said driving rock-shaft.

5. The combination with a sewing machine having a work plate, of ruffling mechanism comprising a rock-shaft disposed longitudinally of the lower portion of the machine, an upwardly extending arm rigidly secured to said rock-shaft, a ruffer blade pivotally connected to the upper end of said arm, arm-stop means disposed rearwardly of said arm, spring means normally holding said arm in retracted position against said stop means, a depending finger attached to said ruffer blade at the rearward end thereof and extending rearwardly of its pivotal connection with said arm, finger-stop means disposed rearwardly of said finger and positioned for contact therewith immediately prior to the contact of said arm with said arm-stop means, and spring means exerting a downward pull on said blade at a point between the working end thereof and its pivotal connection to said arm for holding said blade against said work plate upon the disengagement of said finger from said finger-stop means.

6. The combination with a sewing machine 40 having a main shaft, of ruffling mechanism comprising a driving rock-shaft connected for operation by said main shaft, a driven rock-shaft coaxial with said driving rock-shaft, a ruffer blade, means connecting said ruffer blade for actuation 45 by said driven rock-shaft, a sleeve enclosing the proximate ends of said rock-shafts, means rigidly securing said sleeve to said driven rock-shaft, a plunger carried by and mounted for relative movement with respect to said sleeve, 50 means normally maintaining said plunger out of engagement with said driving rock-shaft and a lever pivoted at one end and disposed for co-operation with the outer end of said plunger for bringing said plunger into co-operative engagement with said driving rock-shaft, the surface of contact of said lever with said plunger being arcuate and having a radius of curvature equal to the distance between the center of the driving rock-shaft and the outer end of said plunger 55 when the latter is in engagement with said driving rock-shaft.
